UNITED STATES PATENT OFFICE.

MANFORD M. SMICK, OF FORT WAYNE, INDIANA.

LOOSE-LEAF BINDER.

No. 926,901.

Specification of Letters Patent.

Patented July 6, 1909.

Application filed October 23, 1905, Serial No. 284,058. Renewed December 23, 1908. Serial No. 469,010.

To all whom it may concern:

Be it known that I, MANFORD M. SMICK, a citizen of the United States of America, and resident of Fort Wayne, in the county of Allen and State of Indiana, have invented certain new and useful Improvements in Loose-Leaf Binders, of which the following is a specification.

My invention relates to improvements in loose leaf binders, and the objects thereof are to provide a device of its class which will readily roll upon its back from side to side and thus facilitate the handling of the book when in use; and also to construct the device so that all the leaves in the binder will become released from pressure when the sections of the binder are distended and thus permit easy insertion of leaves or the removal thereof, in any portion of the book. These objects are accomplished by the construction illustrated in the accompanying drawings, in which:

Figure 1. is a plan of the device with the front and back covers in open position, portions of the binder being cut away; Fig. 2. is an end view of the same, with portions thereof in section; Fig. 3. is a perspective view of the binder in open position; and Fig. 4. is a detail end view of the locking mechanism.

Similar numerals of reference indicate corresponding parts throughout the several views, and referring now to the same: 1 and 2 are the front and back sections respectively, and 3 is the central section of the binder. The front and back sections are oppositely disposed and the adjacent portions of each telescope into the corresponding sides of the central section and the telescoping portions thereof are hollow. Hinged covers 4 and 5 are connected respectively with the front and back sections and are adapted to open oppositely.

Each of the sections 1 and 2 has fixed upon its inner lower side a plate 6 which has thereon a toothed rack 7, and a pawl 8 is arranged within the central section, and the respective ends of which are adapted to engage the corresponding racks and thereby prevent the front and back sections from becoming distended. An operating rod 9 is mounted longitudinally within the central section and affords support for the pawl 8, the latter having an elongated opening 10 therein,

through which the rod extends, which admits sufficient play for the pawl to move over the teeth of the racks when the front and back sections are moved toward one another. The rod 9 has pins 11 which project upon either side of the pawl so that when the rod is moved longitudinally the pawl will be moved into or from engagement with the toothed racks accordingly.

A rectangular frame 12 is mounted upon the rod 9 and has lips 13 which extend under the corresponding edges of the plates 6 and serve to prevent the rod from springing upwardly and thereby lifting the pawl from locked connection with the toothed racks. A bearing 13 is mounted in one side of the frame 12 and affords support for the rod 9, and has mounted thereon a ring 14, the latter being of the variety used in combination locks and may be of any suitable character. A wing 15 is fixed upon the side of the rod 9 and is adapted to pass through the bearing 13, and ring 14, when the rod 9 is drawn longitudinally outward, the bearing and ring having suitable recesses 16 and 17 for that purpose. When the rod 9 is in innermost position, it may be turned so that the wing 15 will engage the pin 18, which projects from the ring 14, and thus manipulate the latter. When the recess 17 in the ring does not register with the recess 16 in the bearing the rod 9 will be prevented from being drawn out, but when said recesses are made to register, by manipulating the ring 14, the wing 15 may then be drawn into the registering recesses so as to admit of longitudinal movement of the rod 9. When the rod is in innermost position the pawl engages the toothed racks, and when the rod is drawn outward, the pawl will accordingly be withdrawn from engagement with the toothed racks, and thus allowing the front and back sections 1 and 2 to become

distended. Springs 19 extend transversely through the central section and act oppositely against the front and back sections within the hollow telescoping portions thereof and tend to hold said front and back sections distended. To prevent the front and back sections from becoming completely withdrawn from the central section 3, a pin 20 is fixed near the inner edge of each of the front and back sections, and each pin ranges within the frame 12 and

comes into contact with the corresponding end of the frame and thereby limits the outward movement of the corresponding section.

A spring 21 is arranged within the central 5 section and acts downwardly upon the ends of the pawl 8 for the purpose of holding it into engagement with the toothed racks.

The front and back sections each have 10 horizontal projecting pins 22 which range above the central section 3, the pins of one section being set to one side of those of the other section and parallel therewith. The pins are adapted to extend through suitably 15 perforated leaves such as are ordinarily used in loose leaf books.

A feature of this invention is in the form of 20 the outer upturned sides of the front and back sections which form, together with the central section, the back of the book. The 25 said sides of the sections recede toward the back and thereby facilitate handling the book, especially when rolling it upon its back from one side to the other as is frequently done in referring from one part of the book to another.

Another feature of this invention is that the locking mechanism and the distending 30 springs are contained within the hollow telescoping portions of the several sections and are concealed thereby, and consequently do not obstruct or interfere in any manner with the inner edges of the leaves.

Having described my invention what I 35 claim as new and desire to secure by Letters Patent, is:

1. In a loose leaf binder, a front and back section; a central section intervening between the front and back sections, the latter sections being oppositely disposed and the 40 adjacent portion of each telescoping into the corresponding side of the central section and being adjustable therein; and locking mechanism concealed within said sections for locking the same in adjusted position.

2. In a loose leaf binder, two oppositely disposed adjustable sections forming respectively the back and front of the binder, each of said sections having a slanting face adjacent its rear portion.

3. In a loose leaf binder, a front and back section; a central section intervening between the front and back sections, the latter sections being oppositely disposed and the adjacent portion of each being hollow and 50 telescoping into the corresponding side of the central section and being adjustable therein, the front and back sections each having an upturned side the rear face of which recedes toward the back of the binder; a hinged 55 cover in connection with the respective upturned sides of the front and back sections; pins projecting from the inner face of the upturned side of each section, the pins of one section being set to one side of those of the 60 other section; and locking mechanism con-

cealed within said sections for holding the front and back sections in adjusted positions.

4. In a loose leaf binder, a front and back section, each having pins for holding the leaves of the book; a central section intervening between the front and back sections, the latter sections being oppositely disposed and the adjacent portion of each telescoping into the corresponding side of the central section and being adjustable therein; an operating rod mounted longitudinally in the central section; a plate secured in each of the front and back sections; a frame mounted upon the rod within the central section and having sliding connection with each of 70 said plates; a toothed rack in each of the front and back sections; and a pawl in connection with the rod adapted to engage respectively the toothed racks, the said rod being adapted to move said pawl from engagement with said racks. 75

5. In a loose leaf binder, a front and back section; a central section intervening between the front and back sections, the latter sections being oppositely disposed and the 90 adjacent hollow portion of each telescoping into the corresponding side of the central section and being adjustable therein; an operating rod projecting within the central section, means controlled thereby for engaging 95 and holding the front and back sections in adjusted positions; and suitable mechanism for locking said rod.

6. In a loose leaf binder, a front and back section; a central section intervening between the front and back sections, the latter sections being oppositely disposed, and the adjacent portion of each being hollow and telescoping into the corresponding side of the central section and being adjustable therein; 100 pins projecting from each of the front and back sections adapted to hold the leaves of the book; springs intervening between the front and back sections within the hollow portions thereof which tend to hold the latter distended; and suitable locking mechanism contained within the central section 105 adapted to engage and hold the other sections in adjusted positions. 110

7. In a loose leaf binder, two oppositely disposed sections forming respectively the back and front of the binder, a central section interposed between the front and back section and having adjustable connection therewith, the back of the central section being flat and the front and back sections each having a slanting face adjacent its rear portion. 115

In testimony whereof I affix my signature, in presence of two witnesses. 120
